UNITED STATES PATENT OFFICE

146,893

DESIGN FOR AN AUTOMOBILE GRILLE BAR

Harry Thomas Bannister, Royal Oak, Mich., assignor to Chrysler Corporation, Highland Park, Mich., a corporation of Delaware

Application December 29, 1945, Serial No. 125,115

Term of patent 7 years

(Cl. D14—6)

To all whom it may concern:

Be it known that I, Harry Thomas Bannister, a citizen of the United States, residing in the city of Royal Oak, county of Oakland, and State of Michigan, have invented a new, original, and ornamental Design for an Automobile Grille Bar, of which the following is a specification, reference being had to the accompanying drawing, forming part thereof, in which:

Fig. 1 is a front elevational view of the automobile grille bar showing my new design;

Fig. 2 is a top plan view of the same;

Fig. 3 is an end elevational view thereof looking at the right end of Fig. 2; and

Fig. 4 is a cross sectional view taken on the line 4—4 of Fig. 2.

The characteristic features of my design are shown in the full lines in the drawing.

I claim:

The ornamental design for an automobile grille bar, substantially as shown and described.

HARRY THOMAS BANNISTER.
